E. T. MURRAY

OIL WELL SWAB

Filed June 27, 1922

Inventor.
E. T. Murray.

By
C. C. Hines,
Attorney.

UNITED STATES PATENT OFFICE.

EDGAR T. MURRAY, OF FORT WORTH, TEXAS.

OIL-WELL SWAB.

Application filed June 27, 1922. Serial No. 571,136.

To all whom it may concern:

Be it known that I, EDGAR T. MURRAY, a citizen of the United States, residing at Fort Worth, in the county of Tarrant and State of Texas, have invented new and useful Improvements in Oil-Well Swabs, of which the following is a specification.

This invention relates to oil well swabs, such as are used for drawing water and other foreign substances from an oil or gas well for a cleansing action, in order to restore or renew the flow of oil or gas.

One object of the invention is to provide a construction which allows fluid and fine solid substances to pass into and upward through the swab, while excluding obstructing substances, thus preventing choking of the swab, an objection to swabs of the type in common use.

Another object of the invention is to provide novel and improved means for affording relief, when the pressure in the well above the swab causes the packing to unduly expand and bind, inhibiting its extraction or upward movement, whereby the excess pressure above may be removed, allowing the swab to be easily raised or extracted and preventing breaking of the parts which might otherwise occur.

A still further object of the invention is to provide a swab which is simple, reliable and inexpensive in construction, and generally more efficient than the swabs in common use.

The invention consists of the features of construction, combination and arrangement of parts, hereinafter fully described and claimed, reference being had to the accompanying drawing, in which:—

Figure 1 is a vertical longitudinal section through a well swab embodying my invention, showing the parts in normal position,

Figure 2 is a similar view illustrating the opening of the valve for a relief action,

Figure 3 is a detail view of the valve seat, and

Figure 4 is a detail view taken on line 4—4 of Figure 1.

Referring now more particularly to the drawing, 5 represents the head or body portion proper of the swab, the upper end of which is reduced and exteriorly threaded as at 6 for application to the well rod or other apparatus, and the internal bore 7 opening

inwardly from the lower end of the head 55 threadedly receives the upper end of a mandrel or tube indicated at 8. The tube or mandrel 8 supports the flanges 9 and swab rubber members 10, a nut 11 near the lower end of the tube holding these members properly in place.

The internal bore 7 has communicating therewith the inner ends of divergent openings 12, through which fluid may pass to and from the said internal bore. A valve seat indicated at 13 is disposed within the bore 7, and a ball or other suitable form of valve 14 rests upon this seat. This seat is in the form of a tubular member as shown particularly in Figure 3, the said member having an annular flange 15 thereon, intermediate its ends, adapted to rest upon the upper extremity of the mandrel 8. By constructing the seat in this manner it is apparent that the same is readily reversible. The ball 75 14 is of such size as to snugly engage the uppermost seat and to tightly close the same under normal conditions.

Disposed within the mandrel 8 near the upper end thereof is a spider or guide indicated at 16, through which slidably passes the valve actuating rod indicated at 17. This rod extends downwardly through the tube or mandrel and is provided at its lower end with a casing engaging device as shown. 80 This device consists of a length of spring metal bent upon itself to provide oppositely arranged curved arms 18, and the central portion of this member is secured to the lower extremity of the valve stem as shown. 85 The ends of this spring member are provided with longitudinally disposed slots indicated at 19, through which the valve stem 17 passes. The ends of the member 18 are disposed in superposed relation as shown, and the slots 19 therein are of sufficient length to permit of a variation of movement in the said arms.

The lower end of mandrel 8 is provided with laterally disposed openings as shown 100 at 20, through which gas or liquid may pass.

In operation, the tool is assembled in the manner shown in the drawing, and adjustment of the rubber devices is made in the usual manner to adapt the swab to the particular casing. The swab is lowered into the casing and the laterally disposed arms 18 of the valve actuating device engage with

the sides of the casing and offer some slight resistance to the downward passage of the swab. This resistance, while not sufficient to retard the movement of the swab itself, 5 causes sufficient binding action to move the valve stem 17 upwardly until the upper extremity thereof passes through the valve seat 13 and engages beneath the ball 14, unseating the latter. It is apparent, therefore, 10 that free passage of liquid above the swab to the lower end of the mandrel will be permitted, thus reducing the pressure above the swab. When the swab is drawn upwardly, the friction of the arms 18 against the casing 15 will retard the valve stem 17, whereupon the latter will be drawn downwardly to permit the ball 14 to seat.

It is apparent from the foregoing that I 20 have provided improvements in devices of this character which will at once overcome the disadvantages heretofore encountered with devices used in similar capacities, and one wherein the several parts are so constructed and arranged that danger of 25 arrangement of the several parts is reduced to a minimum.

While the above is a description of the invention in its preferred form, it will be understood that various changes in the 30 minor details of construction and arrangement of parts may be resorted to if desired, without departing from the spirit of the invention as defined by the claims.

Having thus fully described my invention, 35 I claim:

1. In a device of the class described, a body, a hollow mandrel depending from said body, the said body having a bore in communication with said mandrel and laterally disposed openings establishing communication 40 between the bore and the exterior of the body, a valve in said bore, and means carried by the body whereby the said valve will be unseated when the body is moved in one direction.

2. In a device of the class described, a body having a bore in its lower end, a valve in said bore, a mandrel carried by said body, a rod disposed within said mandrel and 45 adapted to unseat said valve, and spring

arms carried by said rod and extending outwardly therefrom.

3. In a device of the class described, a body having a bore in its lower end, a mandrel engaged in said bore, a valve seat above 55 said mandrel, a stem slidable in said mandrel and projecting below the lower end thereof, friction arms carried by the lower end of said rod, and the upper end of said rod adapted to engage and open said valve when 60 said body is moved in one direction.

4. In a device of the class described, a body having a bore in the lower end thereof, the said body having lateral openings extending therethrough and communicating with said bore, a valve in said bore below 65 said openings, a mandrel carried by said body and depending therefrom, a rod slidable longitudinally within said mandrel and projecting beyond the lower end thereof, and friction arms carried by said rod and projecting laterally therefrom.

5. In a device of the class described, a body having a bore in the lower end thereof, the said body having laterally disposed 70 openings extending therethrough and communicating with said bore, a mandrel engaged in the lower end of said bore, a valve seat resting upon said mandrel, a ball resting upon said seat, a rod slidable within 75 said mandrel and longitudinally thereof, the lower end of said rod projecting below the lower end of said mandrel, and spring arms carried by the lower end of said rod and projecting laterally therefrom.

6. In a device of the class described, a body having a valve therein, a rod slidably carried by said body and adapted when moved in one direction to open said valve, a spring member secured intermediate its 80 ends to the lower end of said rod and having its ends bent inwardly and lying in superposed position adjacent said rod, and the said superposed ends having elongated 85 openings therein through which said rod passes.

In testimony whereof I affix my signature.

EDGAR T. MURRAY.
